UNITED STATES PATENT OFFICE.

FRITZ WALTHER AND GEORG WALTHER, OF ZELLA-MEHLIS, GERMANY.

AUTOMATIC FIREARM.

Application filed August 29, 1921. Serial No. 496,756.

(GRANTED UNDER THE PROVISIONS OF THE ACT OF MARCH 3, 1921, 41 STAT. L., 1313.)

To all whom it may concern:

Be it known that we, FRITZ WALTHER and GEORG WALTHER, citizens of the German Republic, residing at Zella-Mehlis 1, Germany, **5** have invented certain new and useful Improvements in Automatic Firearms (for which we have filed applications in Germany, January 9, 1920; Denmark, May 12, 1920; Norway, June 28, 1920; Austria, June 10 1, 1920; Czechoslovakia, June 21, 1920; Holland, June 2, 1920; Spain, July 17, 1920; Switzerland, May 21, 1920; France, June 30, 1920; Italy, June 29, 1920; Sweden, June 2, 1920; Belgium, June 17, 1920; England, **15** June 24, 1920), of which the following is a specification.

Our invention relates to improvements in automatic fire arms of the type in which the cartridges are fed by means of a slide block **20** which is connected to a convenient moving part of the lock, said slide block being so constructed that after feeding the cartridge it returns the feed device to its original position.

25 The automatic fire arm according to this invention is characterized by the slide block being coupled to the breech block and traveling in a straight line in the receiver, a pin on the feed lever engaging grooves in said **30** slide block in such a manner that the feed lever is raised during the advance of the breech block and therefore of the slide block whereby said feed lever introduces a cartridge into the barrel which cartridge is **35** pushed thereinto by the advancing breech block whilst the feed lever is gradually lowered.

The example of automatic gun according to the invention, as illustrated in the drawings, has a movable barrel, a toggle joint lock, and the magazine is in the front of the stock, but the invention is applicable to guns with a fixed barrel, another kind of lock, and a differently arranged magazine. **40**

45 Details of the gun and its outer appearance are shown in the drawings, in which:—

Figs. 1-26 show the arrangement of the carriage feed from the stock magazine into the barrel and the working of the said device and

50 Fig. 27 shows the general appearance of the gun.

In the said figures:

Fig. 1 is a longitudinal section through the automatic rifle on central line I—I **55** (Fig. 18).

Fig. 2 a longitudinal section on the vertical line II—II (Fig. 18).

Fig. 3 shows the position of the parts in accordance with Fig. 1, more particularly **60** the connection of the slide block with the breech block and the arrangement of the feed lever, the latter dotted.

Fig. 4 shows the locking hook in the position in which it holds fast the feed lever. **65**

Fig. 5 is a cross section of the rifle on line III—III (Fig. 2).

Fig. 6 is a longitudinal section of the rifle in the position in which the locking hook is released by the striking of the cartridge ejected from the magazine, and thus **70** releases the feed lever; section II—II (Fig. 18).

Fig. 7 shows the corresponding position of the slide block and of the feed lever controlled by it. **75**

Fig. 8 shows the position of the locking hook and of the feed lever in accordance with Fig. 6, looking from inside.

Fig. 9 is a cross section on line IV—IV **80** (Fig. 6).

Fig. 10 is a longitudinal section through the lock with the feed lever raised by the slide block, on line I—I (Fig. 18).

Fig. 11 is a section similar to that of Fig. **85** 10, on line II—II (Fig. 18).

Figs. 12-15 illustrate the action of the slide block on the feed lever or on the lateral pin provided on the feed lever.

Fig. 12 is the position corresponding with **90** the position shown on Figs. 10 and 11 with the cartridge raised.

Fig. 13 with the raised cartridge introduced into the barrel.

Fig. 14 when the raised cartridge is **95** pushed by the breech block into the barrel, whilst the feed lever has been lowered again.

Fig. 15 shows the cartridge being pushed into the barrel during the advance of the breech block, the feed lever having already **100** reached its low position.

Fig. 16 shows in plan a section through the receiver on line V—V (Fig. 2) with the feed lever in position.

Fig. 17 shows the same arrangement in horizontal section (Fig. 2) with the feed lever removed.

Fig. 18 is a cross section through the lock 5 on line VI—VI (Fig. 1).

Fig. 19 is an elevation of the slide block.

Fig. 20 is an end view of the same.

Fig. 21 is a section of the same on line VII—VII (Fig. 19).

Fig. 22 is a plan of the said slide block.

Fig. 23 is a section on line VIII—VIII (Fig. 19).

Fig. 24 is an outside elevation of the said slide block with its spring.

Fig. 25 shows the position of the slide block when it is raised by the pin of the feed lever in opposition to the action of its spring.

Fig. 26 shows the slide block in the same 20 position as in Fig. 25, seen from the outside.

Fig. 27 shows the automatic gun in an outside view.

The gun, Fig. 27, comprises a receiver or breech casing A, a cover B movable on the 25 same and into which is screwed the barrel 1, and a stock piece C which is pivoted at D to the barrel and can be turned away from the receiver A after certain locking devices have been released, which stock piece 30 contains the magazine.

When the piece C has been turned away from the barrel 1 by turning it about the hinge D, the stock can be used as a handle for screwing the barrel 1 out of the cover 35 B, this being desirable as in this gun the cover B is closed at the rear end and has therefore, before the barrel can be released, to be unscrewed. The gun can have a shortened recoil for the cover and the barrel, for it is so arranged, that, in spite of the reduced recoil, long cartridges can be used, this being rendered possible by the use of a toggle joint closing device. The cartridge feed from the stock magazine into the barrel chamber 1 is operated by a breech block moved back by the recoil on firing, by means 45 of a slide block driven by the said breech block. This arrangement is illustrated in Figs. 1-26. Its working is substantially as 50 follows:

The breech block during its recoil and the subsequent advance operates a slide block. This block is provided with guides with which engages a pin of the cartridge feed lever. The slide block produces the raising and lowering of the feed lever. In its low position the feed lever is held fast until a cartridge pushed out of the magazine has released a stop hook, whereupon 55 the feed lever acts under the action of the slide block. In order to ensure that only one cartridge issues from the magazine into the barrel, an automatic locking device is provided which retains the remaining cartridges in the magazine. The cover B re-

ceives the barrel 1 and the breech block 2, the latter being operated by a toggle joint locking device 3, 4. The cartridges are pushed out of the magazine 5 by means of a piston 6 controlled by a spring 7 and moved towards the lock, when a locking pin 8 provided on the breech block 2 permits it. The piston 6 is retained by a stop 9 on the magazine tube so that it cannot be driven out of the magazine. In its forward and backward movement, the breech block operates, by means of a pin 10, the slide block 11 which works in a guide 13 in the wall 12 of the receiver. This slide block 11 has at the top and at the bottom cylindrical track 14 faces 14 and 15, by means of which it travels on the upper and bottom surfaces of the rectilinear guide 13, and it carries a spring 16 which tends to press the front end of the slide block (Fig. 19) against the bottom track face of the guide 13. Turning of the slide block 11 about the cylindrical surfaces 14, 15 takes place only when, as shown in Fig. 25, the pin 21 of the feed lever 18 presses the slide block upwards, whereupon the shank of the spring 16 engages with an upper groove 17 in the slide block (Fig. 26). This slide block acts on the feed lever 18 in the following manner:

The feed lever is pivoted on a pin 19 in a part 20 of the receiver (Fig. 1) and it is provided with a lateral pin 21 adapted to travel in the grooves 22, 23 of the slide block 11 (Fig. 3). The pin 21 consequently makes the feed lever 18 oscillate corresponding 100 with the position of the slide block 11 in its rectilinear guide 13, that is to say with the position of the breech block 2, as the breech block 2 operates the slide block 11 by means of the pin 10. The feed lever 18 has an 105 upper cam face 24 which works together with a cam face 25 on the slide block (see Figs. 3, 7 and 12-15). In Fig. 3 the breech block 2 is shown moved forward, the pin 21 being accordingly outside the slide block 11. When the breech block 2 is pushed back (see direction of the arrow Fig. 7), the pin 21 moves in the lower groove 22 of the slide block 11 and, on striking the cam face 26, it raises the slide block 11, the spring 16 being 110 at the same time compressed (see Fig. 7). The pin 21 allows however the slide block to drop downwards, the spring 16 being relaxed, as soon as it has passed it (see Figs. 25, 26, 19). When the breech block 2 is advancing again, the slide block 11 will raise the pin 21 of the feed lever which travels over the cam face 27. In this manner, the feed lever is raised, and also the cartridge 115 28 on the feed lever (Figs. 10-12).

The feed lever remains in the raised position as long as the pin 21 is travelling over the upper cam face 29 (see Fig. 13), whereupon the cam face 24 of the feed lever engages the cam face 25 of the slide block 11, 120

so that, during the advance of the breech block 2 and the consequent advance of the slide block, the feed lever will be slightly lowered (see Fig. 14). Finally the cam face 25 of the slide block 11 on which travels the cam face 24 of the feed lever, will cause again a complete lowering of the feed lever. The feed lever must be held fast in its lowest position whilst a cartridge is in the barrel, 10 to be released only when the breech block 2 is withdrawn, that is to say automatically pushed back by the gases from explosion, and the fired cartridge ejected. For locking the feed lever a locking hook 30 is used 15 (Fig. 8). This locking hook 30 is adapted to pivot around a pin 31 fixed in the casing A. The hook 30 has a cam face 32 which acts upon a face 33 of the feed lever 18 (see Fig. 4), keeping the feed lever 18 thus in 20 lowered position. The locking hook 30 has a slot 34 with which a pin 35 of a fork 36 engages, said fork being rotatably mounted on a pin 37 and provided at its front end with lugs 38 which form abutments for the 25 rearmost cartridge in the magazine 5. A spring 39 tends to depress the fork 36 at its front lug end 38. This results in the following operation described with reference to Figs. 4, 5, 6, 8, 9 and 11.

30 As long as the breech block 2 is in the forward position and holds the cartridge in the barrel 1, the rearmost cartridge 28 in the magazine is held by the stop or pin 8 of the breech block 2. The spring 39 under the 35 action of the fork 36, has so raised the locking hook 30 that the fork is lowered at its front lug ends (Figs. 1, 5) and the lugs 38 no longer engage with the edge of the cartridge 28 but have released the same. The 40 feed lever 18 rests on the fork 36 (Fig. 1). When the breech block 2 moves back, its stop 8 will be also moved away from the cartridge, and the cartridge 28 can slide with the returning breech block 2 on the feed 45 lever 18, as the lugs 38 of the fork 36 no longer oppose this movement of the cartridge. As the recoil of the breech block under the action of the gases from firing takes place very rapidly, the cartridge shell 50 28 advanced by the magazine spring 7 will also be moved back quickly and its edge will strike the locking hook 30. The locking hook 30 is thereby turned about the pin 31. Its projection 32 releases the face 33 of the 55 feed lever 18, so that now, during the subsequent advance of the breech block (which is caused by a recoil counter spring) the feed lever 18 can also be raised by means of its pin 21 under the action of the advancing 60 slide block 11. At the same time however the locking hook 30 in being driven back, has acted by means of its slot 34 on the pin 35 of the fork 36 so that this fork is pressed upwards (see Figs. 6, 9 and 10), its spring 39 being compressed, and the lugs 38 get in 65 front of the next cartridge in the magazine 5 preventing said cartridge from getting under the feed lever (Figs. 6, 9 and 10). In Figs. 6 and 10 it has been assumed that the last cartridge 28 of the magazine is on the feed lever and that the pins 38 of the fork 36 engage with the driving piston 6.

If the magazine 3 however still contains several cartridges, the lugs 38 will act on the edge of the rearmost cartridge as shown 70 in Fig. 9, whereby the other cartridges are prevented from coming out of the magazine during the action of the feed lever 18 and from getting under said feed lever.

The locking of the magazine by means 75 of the lugs 38 continues until the feed lever 18 has been again completely lowered. The advancing breech block 2 has advanced the slide block 11 so far that the pin 21 of the feed lever 18, sliding in the groove 22 and meeting with resistance at the cam face 26, has been lowered so that the face 33 of the feed lever 18 is caught by the projection or lip 32 of the locking hook 30 (Fig. 4). At this moment the fork 36 is however lowered, 80 owing to the corresponding turning of the locking hook 30 and under the action of the spring 39, and its lugs 38 release the new cartridge in the magazine, any other advancing cartridge being at once pushed back into the magazine by the stop 8 of the breech block 2.

The release of the locking hook is therefore effected by the cartridge 28 being forced out of the magazine, and it is only 85 the release of the locking hook, which causes the release of the feed lever, so that the feed lever can be raised by the advance of the breech block 2 and therefore of the slide block 11, owing to the engagement of the pin 21 90 with the cam face 27 of the slide block. If the locking hook 30 were not released, the pin 21 of the feed lever 18 would remain in front of the slide block 11 and find an 95 abutment on the cam face 27 that is to say on the front face of the slide block, and consequently the breech block could not return, being coupled with the slide block 11 by the pin 10. In order to enable the breech block to be advanced again by the closing 100 spring, after the last cartridge has been fired, a hand release for the locking hook 30 is provided. Under the fork 36 in the receiver a rod 40 is mounted so that it can 105 pivot around pins 37. This rod is depressed by the spring 42 at its front end the latter projecting at 43 from the receiver. The rod 40 acts on a bridge 44 arranged on the fork 36, on the said fork. When the front end 110 43 of the rod 40 is forced into the lock, and when the fork 36 is thus raised, the fork 36 will operate, by means of the pin 35 and slot 34, the locking lever 30 and pull the same 115 away from the feed lever so that the slightly raised feed lever will allow the pin 21 to 120

125 130

pass over the cam face 27 and to cause a movement of the feed lever without any cartridge being on the feed lever. The breech block 2 can now be advanced again 5 by a spring so that it closes the lock chamber.

The fork 36 and the rod 40 could also be made in one piece. The operation of the cartridge feeding device is accordingly as 10 follows:—

As long as the breech block 2 closes the barrel 1, the magazine 5 is closed by the stop 8 of the breech block and no cartridge can get from the magazine on the feed lever. 15 On the cartridge being fired, the breech block 2 is driven back and the rearmost cartridge 28 of the magazine 4 moves freely back on the feed lever 18, as the stop 8 of the said cartridge 28 allows it to pass freely, 20 the cartridge being driven on the feed lever by the action of the spring 7 of the magazine. The breech block 2 retracts at the same time, by means of the pin 10, the slide block which allows the pin 21 to pass 25 through its lower groove 22 (Fig. 7). The feed lever 18 which is in its lowest position, is locked in this position by the projection 32 of the locking hook 30 acting on its stop 33. The breech block goes back to its rear- 30 most position and at the same time, by means of the cartridge extractor 45, pulls back the cartridge shell which is expelled by an ejector. In the meantime the last cartridge 28, released by the returning stop 8 of the 35 breech block 2, has been pushed by the magazine spring 7 onto the feed lever 18 where it strikes the locking hook 30 and presses the same back. In this manner, owing to the projection 32 being forced away from 40 the face 33 of the feed lever 18, said feed lever is released. The locking hook 30 which is moving back, depresses the fork 36 at its rear end, so that the front fork lugs 38 engage with the bottom of the next cartridge 45 in the magazine or with the piston 6 of the magazine.

Owing to the cartridge 28 on the feed lever 18, being in an oblique position, the lugs 38 can easily get between the cartridge 50 28 on the feed lever and the cartridge in the magazine, or the push piston 6 (Fig. 6).

Owing to the raising of the fork 36, the feed lever 18 will also be somewhat raised so that the pin 21 of the feed lever 10 is 55 brought into such a position that the pin 21 engages with the cam face 27 of the slide block 11, said slide block 11 having been lowered by the pressure of the spring 16 upon its lower rectilinear guide track. The 60 feed lever 18 is thus raised also (Fig. 12) and remains in the raised position, as the cam face 29 adjoining the cam face 27, is parallel to the bottom guide surface 13. The feed lever remains raised until it engages 65 again by means of its cam face 24 with the

cam face 25 of the slide block which advances again with the breech block (Fig. 13). The cartridge 28 advanced by the breech block 2, is therefore moved towards the barrel, and the feed lever 18 is gradually lowered (Fig. 14). The advanced breech block 2 pushes the cartridge still further into the barrel (Fig. 15), the pin 21 of the feed lever 18 being brought by the faces 24, 25 into the groove 22, and the feed lever is again 70 completely lowered.

As long as the feed lever is not lowered, the fork 36 also remains in the position in which the lugs 38 are raised, so that the next cartridge of the magazine 5 is prevented from getting into the lock chamber. Only on the feed lever being completely lowered, the front end of the fork 36 will be lowered also, but the rearmost cartridge of the magazine will be retained by the stop 8 of the breech block 2. Owing to the lowering of the feed lever and to the lowering of the fork lugs 38, produced by the said lowering and by the spring 39, the locking hook 30 will be raised, so that it 85 will catch with its projection 32 the cam face 33 of the feed lever and lock the same. The breech block 2 advanced by its closing spring, pushes the cartridge into the barrel so that the gun is ready for firing, 90 the firing pin having also been cocked during the bending of the toggle joint.

If after the last cartridge has been removed from the magazine, the breech block is again to be moved forward, the pin 21 100 of the feed lever must be brought within reach of the cam face 27 of the slide block 11. With this object in view the rod 40, or the fork 36 used instead of the rod 40, is forced with its front end 43 into the lock, 105 whereby the fork is raised and raises on its part the feed lever 18 in such a manner that its pin 21 can engage with the cam faces 27, 29 of the slide block, whereupon the breech block can advance again under 110 the action of the closing spring. In order to hold fast in the gun the rear member 4 of the toggle joint 3, 4 during the return of the cover B and of the movable barrel 1 to the firing position, and to cause thus 115 the bending of the toggle joint and therefore the opening of the breech block, the rear toggle lever 4 has a cam which, on the renewed advance of the cover B finds an abutment on a spring-controlled arm mounted in the receiver A of the gun bending thus the toggle joint and pulling back the breech block, until the cam again passes out of reach of the spring-controlled arm during the renewed advance of the cover 120 and barrel, the toggle joint being now exposed to the action of the recoil spring, and therefore advances the breech block. In the manner described the bending of the toggle joint during the withdrawing of the 125

breech block causes the ejection of the cartridge and the supply of a new cartridge.

The specific toggle action is fully disclosed and claimed in applicants' co-pending 5 application Serial Number 496,757.

We claim:—

1. In an automatic fire arm as described comprising in combination a magazine in the front of the stock, a breech block, a breech casing having straight guide grooves, a feed lever, a grooved slide block coupled with said breech block, a lug on said breech block designed to retain the rearmost cartridge of said magazine in the front of the 10 stock, a pivotally mounted locking hook for retaining said feed lever in its lowest position and designed to be acted upon by the cartridge for releasing the feed lever, a lateral pin on said feed lever guided in the grooves of said slide block designed to be raised to its highest possible position together with said feed lever by the action of the advancing slide block.

2. In an automatic fire arm as described 25 comprising in combination a magazine in the front of the stock, a breech block, a breech casing having straight guide grooves, a feed lever, a grooved slide block coupled with said breech block, a lug on said breech 30 block designed to retain the rearmost cartridge in said magazine, a pivotally mounted locking hook for retaining said feed lever in its lowest position and designed to be acted upon by the cartridge for releasing the feed lever, a lateral pin on said feed lever guided in the grooves of said slide block designed to be raised to its highest position together with said feed lever by the action of the advancing slide block, a pivotally mounted fork, end lugs on said fork designed to come in contact with the 35 rearmost cartridge of the magazine after said locking lever has been released so that the rearmost cartridge is retained from getting upon the feed lever until said lever has returned to its lowest position.

3. In an automatic fire arm as described comprising in combination a magazine in the front of the stock, a breech block, a breech casing having straight guide grooves, a feed lever, a grooved slide block coupled with said breech block, a lug on said breech block designed to retain the rearmost cartridge of said magazine in the front of the 50 stock, a pivotally mounted locking hook for retaining said feed lever in its lowest position and designed to be acted upon by the cartridge for releasing the feed lever, a lateral pin on said feed lever guided in the grooves of said breech casing designed to be raised to its highest position together with said feed lever by the action of the advancing slide block, a pivotally mounted fork, end lugs on said fork designed to come 55 in contact with the rearmost cartridge of the

magazine after said locking lever has been released so that the rearmost cartridge is retained from getting upon the feed lever until said lever has returned to its lowest position, a rod under said fork, adapted to be operated by hand, a bridge on said fork designed to be acted upon by said rod so that the feed lever is raised and its pin brought into the path of the slide block to release the locking hook in case there should not be a cartridge to effect this. 70

4. In an automatic fire arm as described comprising in combination a magazine in the front of the stock, a breech block, a breech casing having straight guide grooves, a feed lever, a grooved slide block coupled with said breech block, a lug on said breech block designed to retain the rearmost cartridge of said magazine in the front of the stock, a pivotally mounted locking hook for retaining said feed lever in its lowest position and designed to be acted upon by the cartridge for releasing the feed lever, a lateral pin on said feed lever guided in the grooves of said slide block designed to be raised to its highest position together with said feed lever by the action of the advancing slide block, a pivotally mounted fork, end lugs on said fork designed to come in contact with the rearmost cartridge of the magazine after said locking lever has been released so that the rearmost cartridge is retained from getting upon the feed lever until said lever has returned to its lowest position, a rod under said fork adapted to be operated by hand, a bridge on said fork designed to be acted upon by said rod so that the feed lever is raised and its pin brought into the path of the slide block to release the locking hook in case there should not be a cartridge to effect this. 80

5. An automatic fire arm comprising in combination a feed lever, a breech casing having straight guide grooves, a breech block, a grooved slide block coupled with said breech block having cylindrical track faces and a cam face, a spring on said slide block designed to press the front end of the same against the bottom track face of its guide path, a lateral pin on said feed lever adapted to travel in the grooves of said slide block so that the slide block on the rearward movement of the breech block is oscillated and on the return movement said lateral pin of the feed lever running up the cam face of said slide block raises the feed lever, the cartridge being fed into the barrel and inserted in the same through the advancing breech block while the feed lever is being lowered. 95

6. An automatic fire arm comprising in combination a feed lever, a breech casing having straight guide grooves, a breech block, a grooved slide block guided in said straight grooves coupled with said breech block hav- 100 110 115 120 125 130

ing an upper cam face, a curved cam on said feed lever designed to act upon said upper cam face of the slide block during its advance, a lateral pin on said feed lever guided in the grooves of said slide block so that the lever on the forward movement of the breech block and consequently of the slide block is raised, the cartridge fed into the barrel and inserted in the same through the advancing breech block while the feed lever is being lowered.

7. An automatic fire arm as described comprising in combination a magazine in the front of the stock, a breech block, a breech casing having straight guide grooves, a feed lever, a grooved slide block coupled with said breech block, a lug on said breech block designed to retain the rearmost cartridge in said magazine, a pivotally mounted locking hook for retaining said feed lever in its lowest position and designed to be acted upon by the cartridge for releasing the feed lever, a lateral pin on said feed lever guided in the grooves of said slide block designed to be raised to its highest position together with said feed lever by the action of the advancing slide block, a pivotally mounted

fork, end lugs on said fork designed to come in contact with the rearmost cartridge of the magazine after said locking lever has been released so that the rearmost cartridge is retained from getting upon the feed lever until said lever has returned to its lowest position, a rod under said fork adapted to be operated by hand, a bridge on said fork designed to be acted upon by said rod so that the feed lever is raised and its pin brought into the path of the slide block to release said locking hook in case there should not be a cartridge to effect this, and a spring acting upon said fork to return said fork to the lowered position.
